UNITED STATES PATENT OFFICE.

JOHN CORNELIUS BELL, OF LONDON, ENGLAND.

MASSAGE APPLIANCE.

Application filed March 6, 1923. Serial No. 623,232.

To all whom it may concern:

Be it known that I, JOHN CORNELIUS BELL, a citizen of the German Republic, residing at 40 Baker Street, Portman Square, London, 5 W. 1, England, have invented certain new and useful Improvements in or Relating to Massage Appliances, of which the following is a specification.

This invention relates to appliances for 10 massaging the human body and to that type of appliance comprising a plurality of rows of rollers or balls mounted on spindles which are secured to a flexible frame.

The object of the invention is to provide 15 an improved construction of the above mentioned type.

To this end, a massage appliance constructed in accordance with this invention comprises a plurality of rows of rollers 20 mounted on spindles arranged transversely across a resilient metal frame, said rollers being disposed both inside and outside of said frame and said frame being provided with a handle rigidly attached thereto.

25 The said resilient frame is preferably composed of spring steel and one extremity thereof may be curved upwards.

The invention will now be described with 30 reference to the accompanying drawing which is a perspective view of one form of massage appliance constructed in accordance with this invention.

The appliance consists of a rectangular frame *a* of spring steel, one end of which is

curved upwards as at *b*. The other end of 35 the frame is provided with a handle *c*. *d*, *d*, *d* . . . are a plurality of spindles secured transversely across the frame *a* and on which are mounted the rollers *e*, *e*, *e* . . . Each spindle has mounted thereon two rollers adjacent one another in said frame and one each on the outside edge thereof although I do not limit myself to the number of rollers employed.

The frame may be made in any convenient 45 size and any suitable number of rows of rollers may be provided. The rollers may be substantially spherical or substantially cylindrical and may be composed of any suitable material, for example, glass or other vitreous substance, stoneware, ivory, bone or the like.

Claim:

A massage appliance comprising a frame 55 made up of spaced and substantially parallel substantially rigid resilient frame members connected at one end, a handle secured to this end, a plurality of spindles mounted transversely of said frame and extending therebeyond on both sides, globular rollers 60 on each spindle between said frame members, and globular rollers freely mounted on the ends of said spindles outside of said frame.

In testimony whereof I have hereunto set 65 my hand.

JOHN CORNELIUS BELL.
